UNITED STATES PATENT OFFICE.

ARCHIE M. BROWN, OF AKRON, OHIO, ASSIGNOR TO THE FIRESTONE STEEL PRODUCTS COMPANY, OF AKRON, OHIO, A CORPORATION OF OHIO.

METHOD FOR MAKING VALVES.

Application filed September 29, 1927. Serial No. 222,921.

This invention relates to methods for making tire or other valves with internal seats.

The general purpose of the invention is to provide an improved method for making valves, whereby certain expensive boring and counterboring operations heretofore employed in order to form a seat for the valve "insides" within the valve body may be obviated.

10 The foregoing and other purposes are attained by the method illustrated in the accompanying drawings and described below. It is to be understood that the invention is not limited to the specific form thereof shown and described.

Of the accompanying drawings,

Figure 1 is a section through a valve body drilled in preparation for the seat forming operation;

20 Figure 2 illustrates the seat forming punch; and

Figure 3 illustrates the completed valve body, the seat forming punch being shown in dotted lines.

25 Referring to the drawings, the valve body 10 is first drilled with the large bore 11 and the reduced bore 12 in which the valve insides are housed, the reduced bore being longer than desired in the finished valve body in which the seat for the insides is to be between the large and small bores, as indicated at 13.

30 A punch 14 is then utilized of a diameter such that it will slidingly fit the large bore, the punch being formed with a reduced stud 15 on its end to form the air duct 13* through the seat portion 13. The punch 14 is forced through bore 11 into engagement with the shoulder at 16 and upsets the metal about bore 12 against stud 15 to form seat 13. The valve body is then ready to receive the usual insides which engage upon seat 13.

35 It will appear from the foregoing that an exceedingly simple method has been provided for forming valve bodies by which a number of difficult and expensive seat-forming operations are avoided. It is also apparent that

modifications of the invention may be resorted to without departing from the spirit of the invention or the scope of the appended 50 claims.

What is claimed is:—

1. That method for forming tire valve bodies with internal seats which comprises forming the valve body with a large bore extending from its base end and a smaller bore adjacent its cap end for receiving the valve insides with the small bore longer than desired in the finished valve, and forming a seat for said insides between said bores by upsetting the metal of the small bore with a punch substantially the diameter of the large bore and formed with a reduced stud on its end, said punch being forced through the large bore into engagement with the shoulder between the bores, the metal being upset to the point at which the seat is desired and against said stud to form an air duct through said seat.

2. That method of forming tire valve bodies with internal seats which comprises forming the valve body with a large bore extending from its base end and a smaller bore adjacent its cap end for receiving the valve insides with the small bore longer than desired in the finished valve, and forming a seat for said insides between said bores by upsetting the metal of the small bore with a punch substantially the diameter of the large bore, said punch being forced through the large bore into engagement with the shoulder between the bores, the metal being upset to the point at which the seat is desired.

3. That method of forming an internal seat in valve bodies, which method comprises forming bores of different diameters in said body with the shoulder between the bores at a point removed from the desired position of the seat in the small bore, and upsetting the metal about the small bore from said point to form said seat at said position in the small bore.
